UNITED STATES PATENT OFFICE

2,480,460

ADJUSTABLE AND COLLAPSIBLE COT
STRUCTURE-PANEL

Robert R. Freund, Mount Carmel, Ill.

Application August 11, 1944; Serial No. 548,987

3 Claims. (Cl. 5—114)

1

This invention relates to a collapsible cot, litter and the like which is capable of a multiplicity of uses, particularly in association with an invalid, hospital or articulated bed structure.

The chief object of this invention is to provide a device capable of the aforesaid as well as other uses to be described.

The chief feature of the present invention resides in two pairs of extensible and collapsible sections, which are capable of independent and conjoint uses, and connecting means for such pairs when utilized in the latter use.

Other objects and features of the invention will be set forth hereinafter.

For clearness, the padding, etc., is omitted and same may be a supplementary addition or a permanent one as desired.

The full nature of the invention will be understood from the accompanying drawing and the following description and claims:

In the drawings Fig. 1 is a perspective view of a hospital bed with its sections in horizontal or bed position, an overhead fracture frame carried thereby, a sling suspended therefrom and the invention suspended thereby in litter formation.

Fig. 2 is a longitudinal sectional view of a pair of collapsible and extensible sections of the litter and in that formation.

Fig. 3 is a transverse sectional view taken on line 3—3 of Fig. 2 and in the direction of the arrows.

Fig. 4 is a perspective view of the invention when utilized as a cot, table or bench.

Fig. 5 is a vertical section through a leg thereof and the immediately associated parts.

Fig. 6 is a rear view of a bed with head section elevated, one of the cot sections being illustrated in its bed mechanism concealing position (storage position), the other being partially removed.

Fig. 7 is a transverse section showing the bed mounting of the cot sections and certain of the associated parts.

Fig. 8 is a perspective view of a hospital bed, with its sections in horizontal position and the cot sections positioned thereon in side guard position.

In Fig. 1 of the drawings 10 indicates a frame having caster supports 11 and supporting head section 12, seat section 13 and detachably supported standards 14 with cross bar 15. The bed includes a sanitary fixture 16 supported as at 17 and adapted to serve as a head board when positioned as shown in Fig. 1. The leg section 18 pivotally connected to seat section 13 at 19 is pro-

vided with an adjustable foot rest having a foot board 20.

A block and tackle 21 is suspended from cross bar 15 as at 22 and cable end 23 is arranged to raise and lower the four slings 24 in the form of two straps, each passing through a snap hook 25. The ends of said sling straps pass through snap hooks 26 by which the slings are secured to opposite ends of cross bar structures 27.

This member 27 is shown more clearly in Fig. 7 and includes a base strap with similarly directed and inturned ends 28. Same and the adjacent parallel portion are apertured at 29 and 30. A U-shaped strap 31 with its ends secured to strap 27 and midbraced as at 31a provides two sockets, see Figs. 4, 6 and 7. Each snap hook 26 engages in aperture 29.

Lying on base straps 27, see Fig. 1, are two pairs of hinged connected cot or litter-forming sections 33. Each may be channel bordered as at 34, see Fig. 2. Space blocking 35 is secured to said member 33 as illustrated and to the under face of said member and at adjacent ends thereof.

Hinge means 36 secured to the blocks 35 hingedly connects the two sections together. Secured to the under face of each member 33 adjacent block 35 as at 37 is corrugated plate 38 forming elongated tubular guides 39. The blocks are apertured as at 40. Rods 41, each with an angular end 42, are slidably associated with the aligned guides 39 and apertures 40 to sustain the hingedly connected cot sections together and in coplaner relation.

Whenever it is desired to form a cot, the two pairs of extended sections are seated in the sockets provided by straps 27 and 31 and brace 31a. Associated with each end of said structure is a leg 43 having the anti-friction foot 44 and the upwardly directed spindle 45. The spindle seats in aligned apertures 29 and 30 and the curved free end 28 bears upon the upper end of the leg. In cot formation, as well as litter formation, reinforcing rods 41 are utilized.

Reference will now be had to Figs. 6 and 7. In the former, frame 10 includes cross member 46 at the upper end of the back thereof. The pair of members 27, etc., may be hung upon said member 46 and thus the sockets of said members 27, etc., are superposed. The lower spaced pair, see Fig. 6, nests one pair of folded sections, and the upper pair is about to nest the other pair of said sections. When both pairs of sections are nested, the same form a closure for the rear end of the bed frame and conceal the frame included mechanism for raising and lowering bed sections, etc.

Reference will now be had to Fig. 8 wherein

there is illustrated a still further use of said sections. Herein standards 14 and cross bar 15 are applied to the bed. Then each hingedly connected pair of sections 33 is unfolded and rod locked in aligned relation. Then one of such resulting units is placed on the bed adjacent standard 14 and when both are so placed the bed is provided with side boards for patient retention when desired.

Note fixture 16, footboard 20 and side boards 33 form a well arrangement which is frequently desirable.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A section support and cross member unit including a base strap having its opposite ends reversely bent, and a U-shape strap secured to the first strap opposite the bent ends thereof, the bent ends and the first strap having aligned apertures, the two straps forming a socket for section reception.

2. A section support and cross member unit including a base strap having its opposite ends reversely bent, a U-shape strap secured to the first strap opposite the bent ends thereof, the bent ends and the first strap having aligned apertures, the two straps forming a socket for section reception, and at least one brace member between

said straps to form therewith a plurality of sockets, there being one less brace member than there are sockets.

3. In combination a pair of independent cross members each having a socket forming portion and two similar but oppositely curled apertured ends, a plurality of independent longitudinally extensible and collapsible sections, each section being medianly hinged and foldable for such collapse, said section being terminally engaged in said sockets, and a leg for each curled apertured end and detachably mounted in the aperturing of the curled end, said sockets being adapted also to receive said sections when the latter are collapsed.

ROBERT R. FREUND.
